BASEBALL STRIKE ZONE TARGET

Filed June 20, 1931

George A. Kleb,
H. M. Plaisted,
Attorney.

UNITED STATES PATENT OFFICE

GEORGE A. KLEB, OF ST. LOUIS, MISSOURI

BASEBALL STRIKE ZONE TARGET

Application filed June 20, 1931. Serial No. 545,687.

This invention relates to certain new and useful improvements in base-ball strike zone targets, the peculiarities of which will be hereinafter fully described and claimed.

The main objects of my invention are first, to provide a device for practice work by pitchers that will indicate how they are pitching the balls; second, to indicate whether the pitched balls are passing the plate at heights that would be called "balls" (too high or too low) and whether they would be over the plate in the strike zone (knee-high to shoulder), and be called "strikes"; third, to provide an adjustable sight ball indicating any height in the strike zone; fourth, to provide such a device that can be used with a catcher, or by the pitcher alone; fifth, to provide a back stop and an incline that will return the pitched balls gravitatingly to the pitcher; sixth, to provide such a portable device that can be disposed in any suitable location indoors or out; and seventh, to provide other objects and construction hereinafter described and claimed.

In the accompanying drawing, on which like reference numerals indicate corresponding parts,

Fig. 1 represents a perspective view illustrating the use of my device;

Fig. 2, a front view of my target;

Fig. 3, a plan view of the same;

Fig. 4, a detail of the post bearing in the disc base; and

Fig. 5, a detail of one end of a detachable elastic cable connection.

When pitchers take up their practice work in the spring to regain their speed and control, they pitch to a catcher over a plate representing the home plate, and round into pitching form. Also prospective pitchers follow the same method and by continued practice obtain the desired speed and control of the ball.

My device is designed to indicate whether the ball is pitched over the home plate in the strike zone between the knee and shoulder of the batter, and to provide a sight ball adjustable to different heights in said zone, so that the pitcher as he obtains control, will have an indicated height in said zone at which

he is to pitch the ball. Furthermore, my device provides means by which the pitcher can carry out his practice work alone without the aid of a catcher to return the pitched balls to him in the pitcher's box located at the regular distance (60 feet) from the home plate. Furthermore, my device is adapted for adjustment to practice work by boys in which the strike zone would be less than for full grown base-ball players. I also provide such a device in a portable form so that it may be located indoors or out in any suitable location for such practice work. Thus it can be transported in knock down condition and readily set up for use in any suitable location.

Referring to the drawing, the numeral 1 designates a rectangular plate of iron or other material having suitable weight to maintain its located position in the portable form of my device, and representing the home plate. Adjacent to said home plate is disposed a base 2, preferably of disc form and of sufficient weight to maintain its located position and support a vertical post 3 having an arm 4 provided with an end portion corresponding in size with the home plate and disposed vertically over the same. This end portion may be formed by a pipe mounted in a four-way connection 5 and providing multiple ends in which are secured eyes 6 vertically over the corresponding eyes 7 at the corners of the home plate 1. This end portion of the arm 4 may be otherwise formed.

I provide vertically disposed cords 8, preferably of elastic cable and having hooks 9 with swivel connection to said cords, adapted to be detachably connected respectively to the eyes 6 and 7 in the end portion of the arm 4 and the home plate. These cords have a middle portion 10 presenting a different color or appearance for a distance approximately that between the knee and the shoulder of a batter, representing the strike zone. Thus the middle portions 10 of the cords may be of red and the end portions above and below may be white or other neutral color, so that the zone portions of the said cords may stand out clearly to the pitcher located in his pitcher's box 11. Thus the pitcher will have a

strike zone clearly indicated as the target for pitching the balls, and can see whether they come within said zone and over the home plate and constitute "strikes". Pitched 5 balls passing outside of said cords would be wild throws and called "balls".

As the pitcher regains his control, and desires to pitch at any definite height within the strike zone indicated by said cords, a sight 10 ball 12 is adjustably mounted adjacent to the sight zone, so that it may be operated by suitable means to dispose it at any desired height at which the pitcher aims to deliver the ball. This sight ball is preferably mounted 15 on a cord 13 passing through eyes 14 in the arm 4, and matching eyes 15 in the disc base, and then down to corresponding eyes 16 at the pitcher's box, so that he may readily adjust the sight ball as described. The 20 operating means for said sight ball may be otherwise located, and the ball itself may be otherwise mounted, but the means described indicate the preferred construction.

In order to indicate the desired curve of 25 the pitched ball and the point at which it "breaks" in front of the home base curved lines 17 are provided from the front sides of the home plate and meeting at a point about 6 feet in front of the plate. These lines may 30 be of white cord or otherwise and serve to inform the pitcher whether his curve ball breaks as desired.

I preferably provide for the practice work 25 of the pitcher by himself without the aid of a catcher, by mounting a back stop 18 of canvas, net or other suitable material, in a loosely hung condition, preferably upon a frame 19 formed by posts inserted in the ground, or carried by suitable cross braces, 40 forming brackets 20, as shown in Fig. 1. Such a portable back stop may thus be located in any desired position back of the home plate.

Disposed across the back stop near its lower 45 end is an inclined conduit 21 preferably secured by hooks 22 to the back stop, to receive the pitched balls as they become dead upon striking the back stop. As shown in Fig. 1, this conduit 21 may be connected to an inclined conduit 23 leading to a box 24 near the pitcher's box so as to return the pitched balls gravitatingly to him for continued use.

In order further to improve the portability 55 of my target, I provide a bearing 25 (Fig. 4) in the disc base, in which is mounted the lower end of the vertical post 3, the bottom end of which has a fixed collar 26 and a matching collar 27 above said bearing. In order to fix the post from turning I provide 60 clamping means such as a clamping collar 28 mounted upon the upper end of the bearing 25 which is partially split at 29 so as to hold firmly the inserted post when the clamping collar is tightened by its bolt 30. Other forms 65 of bearing may be used.

Instead of lifting the base and post to another location, it is made more readily portable by using the disc base as a wheel while grasping the post in the hands and pulling it from its vertical position. 70

Thus when the clamping means is loosened, the post 3 may be turned down by hand to horizontal, and the disc base will serve as a wheel for moving the target to any location. For instance, it may be located on the opposite side of the home plate from that shown 75 in Fig. 1. As the disc base is of concrete or other material having considerable weight, this wheeling action facilitates movement of the target as described. 80

While the height of the post 3 is made to correspond with that of a full grown batter, I provide for adjusting this post and its arm vertically to adapt it for younger players who require a strike zone of lesser vertical 85 height than that suited to full grown players. I have therefore shown the vertical post in two sections, the larger section 3' receiving the upper section 3 as shown in Fig. 4. A set screw 31 serves to hold the upper section of 90 the post in its vertically adjusted position, or other clamping means may be used. The elastic cords will shorten automatically and lessen the height of the strike zone, or such shortening of the strike zone may otherwise 95 be obtained, such as by using shorter cords detachably connected to the home plate and end portion of the arm 4, as previously described, to adapt it for the use of "kids".

The post 3 and arm 4 are preferably connected 100 at their intersection by an elbow 32, and may be readily unscrewed, and the cable cords detached from the arm and home plate when taken down for packing or transportation. Likewise the post may be removed 105 from the base by removing the collars.

I have shown the post as divided into feet 110 for instance, to facilitate the location of the sight ball at any desired level or height from the ground. 115

When the base and post are removed from one side of the home plate to the other, only the front or centrally disposed cord in the central vertical plane of the home plate, is required to be changed in its attachment to the opposite hook 6, which has become the front of the end portion of the arm, and located over the front corner and eye 7 of the home plate. 120

I do not limit myself to the construction herein shown except by the appended claims.

I claim:

1. A device of the character described comprising multiple vertical cords disposed above 125 a home plate and presenting a different appearance in the middle portion than at the ends to indicate the strike zone, a vertically adjustable ball mounted adjacent to said cords for a sight ball indicating any desired 130

level in said zone, and means to mount said ball adjustably, substantially as described.

2. A device of the character described comprising a portable home plate having eyes at its corners, a portable base disposed adjacent thereto, a vertical post mounted in said base and having an arm with multiple ends having eyes correspondingly disposed vertically over said home plate, vertical elastic cable cords having end hooks engaging the respective eyes in the home plate and multiple ends on said arm and presenting a different appearance in their middle portion than at their ends to indicate the strike zone, a vertical adjustable ball mounted adjacent to said cords for a sight ball, and means to mount said ball adjustably to indicate any desired height in the sight zone, substantially as described.

20 3. A device of the character described comprising a portable home plate, a portable disc base having a central bearing, a post on which said disc base is rotatively mounted and having an arm with an end portion corresponding to and disposed over the corners of said home plate, multiple vertical cords detachably connected to said home plate and the overhead end portion of said arm respectively, and clamping means to fix said post in its bearing temporarily and when loosened allow rotation of said base on the post for wheeling to a desired location, substantially as described.

4. A device of the character described comprising multiple vertical cords disposed over a home plate and their middle portions indicating the strike zone, a frame supporting said cords, a vertical adjustable sight ball carried by said frame adjacent said strike zone, and adjustable means for said sight ball to cause said ball to indicate any desired height in the strike zone for the pitched ball, substantially as described.

In testimony whereof I have affixed my signature.

GEORGE A. KLEB.
